FIREARM STOCK CONSTRUCTION

Joseph Thomas Fortin, St. Victer de Beauch, Quebec, Canada

Application June 2, 1939, Serial No. 276,978

3 Claims. (Cl. 42—71)

This invention relates to firearms.

More particularly, the invention relates to a rifle having a folding stock, so that the rifle or the like may be shortened when not in use.

The objects of the invention are to provide a rifle having its stock hinged to the receiver member or action whereby the stock may be turned down or folded to lie below the receiver member when the rifle is not in use.

A specific object of the invention is to so form the stock that it provides a hinged shoulder engaging member or butt, so that the stock can be reduced in size when the rifle is not in use.

Another specific object of the invention is to so form the hinged stock, that when folded against the receiver member, the stock will house and therefore shield the trigger.

Still another specific object of the invention is to provide means for releasably locking the stock in its folded position under the receiver member, or in its extended or normal position, as well as to releasably lock the shoulder butt in operative or in folded position.

In the drawing, wherein like numerals of reference indicate corresponding parts in the various figures.

Figure 1 is a fragmentary side elevation of the rifle;

Figure 2 is an enlarged section on line 2—2 in Figure 1;

Figure 3 is an enlarged fragmentary view showing the stock partly folded;

Figure 4 is an enlarged fragmentary view of Figure 3;

Figure 5 is a fragmentary, bottom plan view 35 of Figure 1;

Figure 6 is a fragmentary top plan view of Figure 1;

Figure 7 is a section on line 7—7 in Figure 6, parts being omitted.

Figure 8 is a fragmentary vertical longitudinal section of the butt portion of the rifle.

Referring now by numerals to the drawing, the rifle A may be in part of a conventional design of which 10 is a barrel secured to a steel base member called the receiving member or action 11, and in which is mounted a trigger 12. 15 indicates the usual lever for operating the usual shell ejecting mechanism (not shown). Instead of providing the usual one piece or solid stock, the invention contemplates the use of a hinged stock. Thus the receiver member or action 11 extends a distance rearwardly of the trigger as at 13, and to this extension is pivoted a member 14 which provides a stock. The stock 14 is pivotally con- 55

nected as by a pin 16 to the inner or rearward end of the extension 13. The stock is preferably formed substantially as shown in Figure 2, comprising a hollow or channel-shaped portion 17 of a depth sufficient to receive and substantially house the operating lever 15 when the stock is folded or turned down to lie under the receiver member. The stock 14 extends rearwardly into a reduced portion 18, which is preferably composed of two spaced bars 19 providing a space or hollow 20 therebetween.

Hinged between the two bars 19, as by pin 20A, is a shoulder member or butt 21. Preferably, a cross bar 22 is provided between and integral with the two spaced bars 19 slightly forwardly of the pin 20A, the bar 22 forming a stop determining the operative or raised position of the butt 21. The forward face of the butt is preferably formed with a longitudinal recess 23 terminating in an aperture or slot 24, which is partly closed by a lug or finger 25 extending in the axis of the recess 23.

In order to releasably lock the butt in its raised or operative position, there is provided a substantially U-shaped spring member 26, anchored at its forward end in the stock. This spring member is so arranged that its free or hook end 30 will penetrate into the slot 24 and engage with or hook onto the lug 25, when the butt is in operative position and bearing against the stop 22. The spring member 26 is preferably formed with a coil or turn 31 in each of its two legs 32 so that the effective length of the member may be slightly increased when it is hooked to the lug 25. The spring is also so arranged that when hooked to the lug it will be under tension and will press firmly on the butt toward the pin 20A. The butt will thus be held securely in operative position. When the butt is not in use and folded back, it lies between the bars 19 which constitute the reduced portion 18 of the stock.

In order to releasably lock the stock in its operative position, a catch or lever 33 pivoted at one end as at 34 to one leg of the channel-shaped portion of the stock, and sliding at the other end in a slot 35 formed in the other or opposite leg of the reduced portion of the stock, is adapted to engage in a slot or recess 36 formed into the extension 13, the extension preferably being formed with a slanted or bevelled face 37 in the length of which is included the slot 36. The locking lever or catch 33 will thus be guided gradually to the slot when the stock is turned rearwardly from its folded position to its extended or firing position. A coiled spring 39 is

tensioned between a lug 38 on the catch and a pin or eye 40 anchored in the stock. The spring will thus urge the lever or catch to a position such that it will engage in the slot 36, and releasably hold the same therein. To turn the catch against the action of the spring 39, and move the catch out of the slot 36, the catch may be formed with an extension 43 sliding through the slot 35 and provided with a finger piece or lug 45.

I claim:

1. A firearm including a receiver member, a stock pivotally mounted to said member to assume a firing position behind said member or a folded position under said member, means for releasably locking said stock in firing position, a shoulder-engaging member pivotally mounted to said stock to assume a raised position, or a folded position adjacent said stock, and means for releasably locking said shoulder engaging member in raised position.

2. A firearm including a stock, a shoulder-engaging member pivotally mounted to said stock to assume a raised position, or a folded position

adjacent said stock, said stock having a hollow space partly defined by a stop, said shoulder engaging member engaging said stop when in raised position and being received and housed in the hollow space when said shoulder engaging member is in folded position, and means on said stock and said shoulder engaging member, including a resilient hook, adapted to releasably lock said shoulder engaging member in raised position.

3. A firearm including a receiver member, a stock pivotally mounted to said member to assume a firing position behind said member, or a folded position under said member, means for releasably locking said stock in firing position, said stock having a hollow space partly defined by a stop, a shoulder-engaging member pivotally mounted to said stock to assume a raised position and engage said stop, or a folded position within the hollow space, and means on said stock and said shoulder-engaging member, including a resilient hook, adapted to releasably lock said shoulder-engaging member in raised position.

JOSEPH THOMAS FORTIN.
